UNITED STATES PATENT OFFICE

2,254,905

EXHAUST MACHINE AND METHOD OF PRO-
TECTING EXHAUST SYSTEMS

Daniel Mullan, Kearny, N. J., assignor to Westinghouse Electric & Manufacturing Company, East Pittsburgh, Pa., a corporation of Pennsylvania

Application November 25, 1938, Serial No. 242,196

24 Claims.

(Cl. 176—2)

This invention relates to machines for gas filling and/or exhausting hollow bodies, and particularly to such used for the manufacture of incandescent electric lamps and similar devices.

In exhaust equipment of the type contemplated and particularly adapted for the evacuation of incandescent electric lamp bulbs, there is in each head assembly a port closing mechanism, usually comprising a rubber tube and pinch clamp, and a compression rubber release mechanism. The purpose of the first named, is to close the exhaust port against atmospheric pressure in the event of a broken lamp or leaker, or an open exhaust port passing a given position. The purpose of the second named, is to hold the exhaust tube of each lamp securely in an air-tight connection by compression of an exhaust rubber.

Heretofore, the development of a leaker or the breaking of a lamp bulb, would result in affecting the exhaust to that extent and depleting the vacuum by the admission of atmospheric air.

In accordance with my invention, I have provided means for closing the port and releasing the compression rubber to permit the removal of the defective lamp, or other device being evacuated, by a single movement of a lever electrically operated by means of a solenoid.

It is, therefore, one of the principal objects of my invention to automatically guard against contamination, or impairment of the exhaust system, by the development of leaks due to such causes as broken or leaky lamps, at a predetermined position in the exhaust schedule.

Another object of my invention is the employment of a Pirani gauge, calibrated to operate at a predetermined pressure through a relay and solenoid, in order to close the pinch clamp and cut off the exhaust equipment from the atmosphere, as well as release the pressure on the rubber receiving the exhaust tube of the defective lamp or device being evacuated, and thereby conserve the vacuum by preventing contamination and depletion by the admission of atmospheric air, as well as facilitate removal of the defective lamp or other device being evacuated.

A further object of my invention is to improve lamp quality through automatic protection of the exhaust system, and relieve the operator from the necessity of observing a signal lamp or other similar means for detecting poor vacuum or broken lamps on an exhaust machine.

A still further object of my invention is the automatic closing of the connection between an exhaust head and the vacuum pump, and the re-

lieving of the compression on the rubber with which the exhaust tube of a device being evacuated connects, by a single movement of a lever operated by a solenoid automatically controlled by a Pirani gauge or other vacuum measuring device.

Other objects and advantages of the invention, relating to the particular arrangement and construction of the various parts, will become apparent as the description proceeds.

Referring to the drawings illustrating my invention:

Figure 1 is a fragmentary plan of an exhaust machine embodying my invention.

Figure 2 is a fragmentary elevational view of the machine on the line II—II of Figure 1, in the direction of the arrows, but showing a slight modification.

Figure 3 is a fragmentary vertical sectional view on the line III—III of Figure 1, in the direction of the arrows, but also showing a valve in the insert gas line.

Figure 4 is a fragmentary view, corresponding to Figure 3, but omitting the inert gas line valve and showing the position of the parts of the head when the pinch valve has been operated to disconnect said head from the vacuum pump valve, and the compression rubber released to allow for the removal of a defective lamp or other device being evacuated.

Figure 5 is a diagrammatic plan view of the machine, fragmentarily illustrated in Figure 1, but showing the arrangement of the pumps and vacuum lines, as well as the circuit controlled by the Pirani tube for automatically closing the connection between the head and the vacuum valve upon the development of a leak.

The present invention may be embodied in any suitable type of exhaust machine, such as used for the progressive evacuation of hollow bodies, and particularly in connection with vacuum or gas-filled electrical devices, such as incandescent lamps, radio tubes and the like.

Exhaust machines for the above mentioned purpose are usually provided with two pumps, a preliminary exhaust pump diagrammatically illustrated and designated in Figure 5 by the reference character 11, and a final exhaust pump diagrammatically illustrated and designated by the reference character 12. The devices to be evacuated, here shown as incandescent electric lamp bulbs and designated by the reference character 13, are first connected with the preliminary pump 11, and exhausted as they travel

with the conveyor 14, while mounted on heads 15, that is, they are moved from one station to another while being exhausted. The same procedure is followed when the devices are subjected to the second or final exhaust pump 12.

In an exhaust machine, such as described and claimed in my Patent No. 2,113,798, dated April 12, 1938, and owned by the assignee of the present application, each conduit from the vacuum pumps to the devices being evacuated, is provided with a plurality of ports 16, arranged to communicate with a plurality of slots 17, disposed in two circular rows and staggered with respect to one another. The conveyor 14 moves with the upper valve section 18, and communication is had with the pumps through the ports 19 in said upper valve section, which successively communicate first with the slots 17 connected to the preliminary pump 11, and then those which connect with the final pump 12, so that a progressive evacuation of the lamp bulbs or other devices, is effected during movement of said devices from the initial position at station number 1, as shown in Figure 5, to station number 16, where each is removed from the exhaust apparatus.

In view of the fact that the gradual exhaust of lamp bulbs and the like, as well as the admission of flushing and filling gas is known to those skilled in the art, and a machine for which the present invention is especially adapted, has been described in my patent, previously referred to, I will not further describe the exhausting operation, simply stating that my invention involves an improvement on the machine of the patent mentioned, especially when said machine is equipped with the type of heads, such as illustrated in Figures 3 and 4.

The machine now being described, is desirably provided with a series of bulb holders, not fully shown, usually termed heads and here designated by the reference character 15. Each bulb holder 15 includes an exhaust port 21. The heads on the machine are of similar construction and, inasmuch as the structure is generally well known in the art and more fully shown in the Mullan patent previously referred to, only the exhaust port 21 and portions associated therewith, are illustrated.

As the heads move with the conveyor 14, the supported lamps or other hollow bodies 13 are progressively connected, first to the vacuum pump 11, and then to the vacuum pump 12, as through line 22, by means of the valve comprising the top section 18 and the bottom section 23. These valve sections are in the form of rings having flat opposed surfaces 24 and 25, with an interposed oil seal fed through passage 26. The top valve section 18 is moved as by a drive shaft, not shown, with the conveyor plate 14 being connected thereto, in any desired manner. Pressure springs, not shown, may serve to hold the upper section 18 in close relation with the lower section 23, which is held stationary as by dowel pins, not shown, extending from said valve section into the frame 21.

The valve sections 18 and 23, which constitute a valve unit, serve to open and close the vacuum lines 16, as well as the inert gas supply lines 28, 29 and 31, if the latter are used, to the bulbs 13 supported in the heads 15. In making gas-filled lamps, each lamp may be first exhausted and then filled with a gas, again exhausted, and finally filled with an inert gas, such as argon, the gas-filling pipe being, in the present embodiment,

designed, designated by the reference character 32.

Each head is desirably provided with an apertured exhaust rubber or conduit 33 in the portion provided with the exhaust port 21. This exhaust rubber is mounted in a fitting 34, to which is threaded a cap 35 provided with a laterally extending arm 36, and adapted to be cam-actuated to either press a washer member 37 through ball bearings 38 against the exhaust rubber 33 to squeeze it about the exhaust tube 39 of the lamp 13 at the proper time, to effect an air-tight connection therewith, or release the pressure thereon to facilitate insertion or withdrawal therefrom. The exhaust rubber connection just described, may be, generally, as shown in the Gustin Patent No. 2,215,100, dated September 17, 1940.

Air is exhausted from the lamp 13 through the exhaust pipe 22, trap 41, and rubber tube connection 42, mounted in the head and adapted to be closed as by means of a pinch clamp 43, forming a valve which may be operated through its arm 43 as desired, or automatically upon the development of a leak, as will subsequently be explained.

Connection with the vacuum pumps 11 and 12 and their manifolds 44 and 45, is effected through lower valve section 23 and vacuum lines 16, by means of rubber hose connection 40; a similar connection providing for the introduction of inert gas, if employed.

In order to effect the actuation of the pinch clamp 43 to close off the vacuum line 22 from the atmosphere in case the bulb 13 leaks or is broken, as well as releasing the exhaust rubber 33 to permit removal of the bulb 13 and/or exhaust tube 39, I provide a vacuum sensitive device, such as a Pirani tube 46, connected to the lower valve section 23, as by means of a pipe 47, and rubber hose 48. This connection is desirably made at what is termed position or station number 12 on the exhaust machine, that is, near the beginning of the final exhaust. The possibility that the exhaust tube of a lamp may not be inserted in every exhaust rubber 33, is desirably taken care of earlier in the exhausting process by automatically closing the pinch clamp 43 of the vacant head at position 4. The purpose of making the Pirani tube connection at this particular point, is to avoid spoiling the final vacuum and ruining lamps, or other devices being evacuated, adjacent the defective device being exhausted, and catch leakers which may not show up until the exhaust is nearly complete.

A Pirani tube comprises a platinum filament 49 in an envelope 51, the resistance of said filament being dependent on its temperature which, in turn, depends on the nature and pressure of the gas surrounding it, so that if a given voltage is applied to said filament, its resistance will vary upon a change of the vacuum from normal. By suitable calibration such a tube may serve, upon depletion of the vacuum to a predetermined extent, to upset the balance of a Wheatstone bridge, designated by the reference character 52, to thereby energize a relay magnet 53, to draw its armature 54, to close a circuit, to be subsequently described, and effect the desired operations.

In the present embodiment, the Pirani tube 46 is shown connected across one side of the Wheatstone bridge 52, balanced against resistances 55, 56 and 57, each desirably of 90 ohms, and closing the other three sides of the Wheatstone bridge 52. Energization of the bridge is effected by connection with the secondary wind-

ing 58 of a transformer 59, through a rectifying unit 61, so that ten volts direct current are, in the present embodiment, applied to two opposite corners of the bridge 52.

The relay magnet 53 in the present embodiment, is indicated as having a resistance of 120 ohms and the winding is such that when the balance of the bridge is upset by the vacuum deteriorating from a normal of less than 25 to 35 microns, to as high as 80 microns, sufficient current passes through the relay to draw the armature 54 to close the circuit 62, supplied from the secondary winding 58, to thereby energize signal lamp 63 and solenoid 64.

The solenoid 64, when energized, raises its armature 65, and moves the connected lever 66 from the position shown in full to that shown in dotted lines in Figure 2 about the pivot 67 in standard 68, connected to the bracket 69 mounted on the frame 27 of the machine. The movement of the lever 66 reciprocates the rod 71 upwardly in its bearing 72, supported in housing 73, also mounted on bracket 69, against the pressure of the coil spring 74, acting between the bracket 69 and the collar 75, secured to the rod 71 as by means of set screw 76. The rod is desirably prevented from dropping below its normal inoperative position by means of a collar 77, secured thereto by set screw 78, and normally engaging the upper end of housing 73.

The rod 71 carries, adjacent its upper end, a cam roller 79 adapted to form an obstruction and operatively engage the arm 36 when raised to the dotted position shown in Figure 3, and a cam roller 81, adapted to form an obstruction and operatively engage the pinch clamp 43 when raised to the dotted position represented in Figure 3, as the conveyor moves to carry the heads from station to station. The roller 81, is pivoted on a reduced section 82 of the rod 71, between a shoulder 83 and the roller 79. The roller 79, is pivotally mounted on a screw 84, threaded to the reduced section 82, as indicated at 85, and disposed between the head 86 of said screw, and the reduced section 82 on the rod 71.

The operation of the apparatus, described in accordance with my invention, will occur if and when a bulb 13 reaches position number 12 on the exhaust machine, and said bulb is either leaking to the extent that the vacuum at that position breaks to a degree, in accordance with the calibration of the Pirani tube 46, which, in the preferred embodiment described, is 80 microns, or the lamp is broken.

Immediately, when one of these events occurs, the normally balanced Wheatstone bridge 52 becomes unbalanced by a decrease in the resistance of the filament 49, resulting in a flow of current between the corners 87 and 88 of the Wheatstone bridge 52, through the relay magnet 53, moving the armature 54 from right to left, as viewed in Figure 5, energizing the signal lamp 63, and closing the circuit through the solenoid 64 to raise the lever 66 and the connected cam rollers 79 and 81, from the full to the dotted line positions shown in Figures 2 and 3, so that they stand in the path of the arm 36 and pinch clamp 43 of the adjacent head 15, to thereby cause the vacuum line 22 to be disconnected from the atmosphere, and the exhaust tube 39 released, to allow removal of the defective or broken lamp 13, and/or its exhaust tube, or other action to overcome the depleting effect on the vacuum, thereby preventing the further manufacture of defective lamps or such insufficiently exhausted.

If it is desired to also conserve the inert fill gas, if lamps of the gas-filled type are being made, the inert gas line 32 may be controlled by a suitable valve therein, comprising, for example, a pinch clamp 91, operated by a suitable cam 92, so connected to the arm 36 that when the exhaust rubber 33 is released, the rubber tube connection 93 in the line 32 is closed, thereby preventing further flow of fill gas therefrom. Such a valve, like the valve 42-43, may be made to operate simultaneously with movement of the pinch clamp 43, and/or movement of the arm 36, if desired, as will be understood.

As a further alternative, the fill or inert gas line 32 may connect directly with the exhaust line 22, as indicated by dotted lines in Figure 2, and designated by the reference character 89, so that the inert gas supply is simultaneously cut off upon closing the tube 42.

From the foregoing disclosure, it will be seen that I have provided means for closing the exhaust port, as well as the inert gas inlet if gas-filled devices are being made, and releasing the compression rubber, by a single movement of a lever automatically controlled and operated by a solenoid. The purpose of and advantages in my invention, are that the exhaust system is protected against contamination in positions subsequent to that at which the Pirani gauge connection is effected, which, in the present embodiment, is position number 12 on the machine, although it will be understood that as an alternative, the connection may be effected at some other point, by closing the exhaust port in case a leaker passes position 12. The pressure is also preferably released on the compression rubber, making it possible for the exhaust tipping torch holder to remove the defective lamp with the exhaust tube at one time.

In normal operation, and in case a leaker reaches position number 12, for example, on the machine, the roller cams 79 and 81 are raised to position to function during movement of the head, from position 12 to position 13. By the use of my invention, an improvement in lamp quality is effected through protection of the exhaust system, and the operator is relieved of the necessity of observing a signal lamp for detecting poor vacuum or defective or broken lamps on the exhaust machine.

Although preferred embodiments of my invention have been disclosed, it will be understood that modifications may be made within the spirit and scope of the appended claims.

I claim:

1. The method of protecting an exhaust system against contamination due to leaks, comprising automatically energizing an electric circuit to close the connection through which a leak would take effect and release any associated leaking device for disconnection from said exhaust system, upon an increase in pressure in said exhaust system beyond a predetermined point.

2. The method of protecting an exhaust system against contamination due to leaks, comprising automatically operating a Pirani tube upon an increase in pressure in said exhaust system beyond a predetermined point, to close the exhaust port and release the compression rubber conduit of the system upon the development of a leak, by a single movement of a lever operable by a solenoid in circuit with a relay controlled by said tube.

3. An exhaust machine comprising a head in-

cluding a rubber conduit adapted to receive the exhaust tube of a device being evacuated, and an arm adapted upon rotation thereof to effect compression of said conduit to grip said exhaust tube therein, and means to automatically move said arm for releasing the exhaust tube of said device for disconnection from the machine, upon an increase in pressure in said machine beyond a predetermined point.

4. An exhaust machine comprising a rotary conveyor, an exhaust head mounted on said conveyor and including a rubber conduit adapted to receive the exhaust tube of a device being evacuated, and an arm adapted upon rotation to effect compression of said conduit to grip an exhaust tube fitted therein, and means facilitating the removal of leaky devices for protecting the exhaust system in said machine against contamination, comprising an electric circuit energized automatically upon an increase in pressure in said system beyond a predetermined point, to close the connection to said head, and move back said rotatable arm to release any associated leaking device for disconnection from said machine.

5. An exhaust machine comprising a rotary conveyor, a plurality of exhaust heads mounted on said conveyor and each including a rubber conduit adapted to receive the exhaust tube of a device being evacuated and an arm adapted upon rotation to effect compression of said rubber conduit to grip such an exhaust tube fitted therein, and means facilitating the removal of leaky devices for protecting the exhaust system in said machine against contamination due to leaks, comprising an electric circuit energized automatically upon an increase in pressure in said exhaust system beyond a predetermined point, to close the connection to the head responsible for a leak, and move the compression arm to release any associated leaking device for disconnection from said machine.

6. An exhaust machine for lamp bulbs, comprising a rotary conveyor, a plurality of exhaust heads mounted on said conveyor and each including a rubber conduit adapted to receive the exhaust tube of a lamp bulb, means to effect compression of said rubber conduit to grip such an exhaust tube fitted therein, and means operable automatically upon an increase in pressure in said machine beyond a predetermined point, and controlled by a Pirani tube, to move a lever and close the connection to the head with which a leaking lamp bulb is associated, and release the compression in said rubber conduit.

7. An exhaust machine for lamp bulbs comprising a rotary conveyor, a plurality of exhaust heads mounted on said conveyor and each including a rubber conduit adapted to receive the exhaust tube of a lamp bulb and an arm adapted upon rotation to effect compression of said rubber conduit to grip such an exhaust tube fitted therein, a valve unit including an upper rotary disc valve section and a lower stationary disc valve section, said sections having flat surfaces in contacting relation and ports lying along said surfaces for effecting transfer of gases therebetween, vacuum lines between the upper valve section and each head, and means for protecting the exhaust system in said machine against contamination due to leaks, comprising an electric circuit energized automatically, upon an increase in pressure in said exhaust system beyond a predetermined point, to close the connection to the head responsible for a leak and release the compression on the conduit which receives the ex-

haust tube of any associated leaking device for disconnection from said machine.

8. An exhaust machine for lamp bulbs comprising a rotary conveyor, a plurality of exhaust heads mounted on said conveyor and each including a rubber conduit adapted to receive the exhaust tube of a lamp bulb and an arm adapted upon rotation to effect compression of said rubber conduit to seal such an exhaust tube fitted therein, vacuum lines including a rubber tube connection to each head, a pinch clamp associated with each rubber tube connection and adapted to be moved to closed or opened position, and means for protecting the exhaust system in said machine against contamination due to leaks, comprising an electric circuit energized automatically upon an increase in pressure in said exhaust system beyond a predetermined point to move the pinch clamp of each head to closed position when said head, upon reaching a predetermined position, is responsible for a leak, and move the arm to release the compression of the rubber conduit to allow for disconnection of a leaking bulb, if connected to said head, for removal from said machine.

9. An exhaust machine for lamp bulbs, comprising a rotary conveyor, a plurality of exhaust heads mounted on said conveyor and each including a rubber conduit adapted to receive the exhaust tube of a lamp bulb and an arm adapted upon rotation to effect compression of said rubber conduit to seal such an exhaust tube fitted therein, and means for protecting the exhaust system in said machine against contamination due to leaks, comprising a Pirani tube so connected that it measures the vacuum in each head as it reaches a predetermined station adjacent the beginning of the final exhaust, an electric circuit between the filament of said tube and one side of a Wheatstone bridge, balanced for normal operation, a relay magnet connected across said bridge, and adapted to operate its armature to close a circuit through a solenoid when the pressure in the Pirani tube increases to a predetermined extent above the normal vacuum, in order to effect closure of the connection to the head responsible for a leak and movement of the compression arm to release any associated leaking device for disconnection from said machine.

10. An exhaust machine for lamp bulbs comprising a rotary conveyor, a plurality of exhaust heads mounted on said conveyor and each including a rubber conduit adapted to receive the exhaust tube of a device being evacuated, an arm adapted upon rotation to effect a compression of said rubber conduit to grip such an exhaust tube fitted therein, and a pinch clamp adapted to close the exhaust connection to said head, and means for protecting the exhaust system in said machine against contamination due to leaks and facilitate the removal of leaky devices, comprising an electric circuit energized automatically upon an increase in pressure in said exhaust system beyond a predetermined point, to actuate the armature of a solenoid and move a lever to transport cam means into position to be engaged by the compression arm and pinch clamp of each head, in order to successively close each exhaust port against atmospheric pressure and release any associated exhaust tube from its rubber conduit.

11. An exhaust machine for lamp bulbs comprising a rotary conveyor, a plurality of exhaust heads mounted on said conveyor and each in-

cluding a rubber conduit adapted to receive the exhaust tube of a lamp bulb, and an arm adapted upon rotation to effect compression of said rubber conduit to seal such an exhaust tube fitted therein, a valve unit including an upper rotary disc valve section and a lower stationary disc valve section, said sections having flat surfaces in contacting relation and ports lying along said surfaces for effecting transfer of gases therebetween, means for moving said upper section with said conveyor, vacuum lines including a rubber tube connection between each head, and the upper valve section, a pinch clamp associated with each rubber tube connection and adapted to be moved to closed or opened position, preliminary and final vacuum pumps, means connecting said pumps to said lower valve section so that, as the upper section and conveyor move, bulbs in said heads are progressively exhausted, a Pirani tube connected to said lower valve section at a station adjacent the beginning of the final exhaust, an electric circuit between the filament of said tube and one side of a Wheatstone bridge balanced for normal operation, a relay magnet connected across said bridge and adapted to operate its armature to close a circuit through a solenoid, when the pressure in the Pirani tube increases to a predetermined extent above the normal vacuum, a lever operable by said solenoid, and cam means movable by said lever upon operation of said solenoid to be engaged by said compression arm and pinch clamp, in order to effect closure of the exhaust port against atmospheric pressure and release of the exhaust tube from its rubber conduit.

12. An exhaust and gas filling machine, comprising an exhaust head including a rubber conduit adapted to receive the exhaust tube of a device to be evacuated, exhaust and gas filling connections to said head, an arm to effect opening and closing of said connections, and means operable automatically upon an increase in pressure in said exhaust connection beyond a predetermined point, to move said arm for closing the exhaust and gas filling connections to said head.

13. The method of facilitating the removal of a leaky or broken hollow device being evacuated and having an exhaust tube clamped in an exhaust rubber conduit by pressure on said conduit, comprising automatically closing the connection to and releasing the pressure on said conduit to free the exhaust tube of said device for disconnection from the exhaust system, upon an increase in pressure in said system beyond a predetermined point.

14. The method of facilitating the removal of a leaky or broken device being evacuated and having an exhaust tube received in an exhaust rubber conduit and gripped by pressure thereon applied to said conduit, comprising automatically energizing an electric circuit to close the exhaust connection to and release the pressure on the exhaust tube of said device, upon an increase in pressure in the exhaust system beyond a predetermined point.

15. An exhaust machine comprising a head with an exhaust connection, including a rubber conduit adapted to receive the exhaust tube of a device being evacuated, an arm adapted upon rotation thereof to effect compression of said conduit to grip said exhaust tube therein, a valve in said exhaust connection, another operating arm extending therefrom, and means to automatically move both of said arms for releasing the exhaust tube of said device and closing said

valve, upon an increase in pressure in said machine beyond a predetermined point.

16. An exhaust machine for lamp bulbs comprising a head, including a rubber conduit adapted to receive the exhaust tube of a lamp bulb to be evacuated, a valve unit including an upper rotary disk valve section and a lower stationary disk valve section, said sections having surfaces in contacting relation and ports lying along said surfaces for effecting a controlled transfer of gases therebetween, vacuum lines including a rubber tube connection between said head and the upper valve section, a pinch clamp associated with said connection and adapted to be moved to closed or opened position, preliminary and final vacuum pumps, means connecting said pumps to said lower valve section so that, as the upper section moves, a bulb in said head is progressively exhausted, a Pirani tube the bulb of which is connected to said lower valve section at a station adjacent the beginning of the final exhaust, the filament of said tube being in the circuit at one side of a Wheatstone bridge balanced for normal operation, a relay magnet connected across said bridge and adapted to operate its armature to close the circuit through a solenoid when the pressure in the exhaust system and Pirani tube bulb increases to a predetermined extent above the normal vacuum, a lever operable by said solenoid, and cam means movable by said lever upon operation of said solenoid to be engaged by said pinch clamp, in order to effect closure of the latter.

17. An exhaust machine for lamp bulbs comprising an exhaust head including a rubber conduit adapted to receive an exhaust tube of a device being evacuated, a pinch clamp adapted to close the exhaust connection to said head, and means for protecting the exhaust system in said machine against contamination due to leaks, comprising an electric circuit energized automatically upon an increase in pressure in said exhaust system beyond a predetermined point to actuate the armature of a solenoid and reciprocate a rod to raise cam means into position to be engaged by the pinch clamp of said head, in order to close the latter.

18. The method of protecting an exhaust system against contamination due to leaks, comprising automatically closing the connection through which a leak would take effect, by energizing an electric circuit upon an increase in pressure in said exhaust system beyond a predetermined point, to cause a rod to reciprocate and carry roller means into position to actuate a valve controlling said connection upon normal movement of said valve toward said roller means.

19. The method of conserving filling gas and protecting an exhaust system against contamination due to leaks, comprising automatically closing the connection through which a leak would take effect and shutting off the filling gas supply upon an increase in pressure in said exhaust system beyond a predetermined point.

20. An exhaust machine comprising a conveyor carrying an exhaust head including a rubber tube for receiving the exhaust tube of a device to be evacuated, a valve in the exhaust connection to said head and having an operating arm extending therefrom, a rod, and a roller supported on said rod, said rod being operable automatically upon an increase in pressure in said exhaust connection beyond a predetermined point, to raise said roller into the path of said arm for closing the valve as the conveyor moves.

21. An exhaust machine comprising a rotary conveyor, an exhaust head mounted on said conveyor and including a rubber conduit adapted to receive an exhaust tube of a device to be evacuated, a valve in the vacuum connection to said conduit, an operating arm extending from said valve, and means for protecting the exhaust system in said machine against contamination due to leaks, comprising a rod, a roller supported on said rod, and an electric circuit energized automatically upon an increase in pressure in the exhaust system beyond a predetermined point, to reciprocate said rod and move said roller into the path of said arm for closing said vacuum connection as the conveyor moves.

22. The method of facilitating the removal of a leaky or broken hollow device being evacuated and having an exhaust tube clamped in an exhaust rubber conduit of an exhaust system by pressure on said conduit, comprising automatically releasing the pressure on said conduit for disconnection of said tube from the exhaust sys-

tem, upon an increase in pressure in said system beyond a predetermined point.

23. The method of protecting an exhaust system against contamination due to leaks, comprising automatically moving a roller upward into the path of movement of the operating arm, of a movable shut-off valve operating arm controlling the connection through which a leak would take effect, to allow it to be engaged by said arm, upon movement thereof, and close said valve upon an increase in pressure in said exhaust system beyond a predetermined point.

24. The method of facilitating the removal of a leaky or broken hollow device having an exhaust tube clamped in an exhaust rubber conduit of an exhaust system by pressure on said conduit, comprising automatically energizing an electric circuit to release the conduit pressure for disconnection of the exhaust tube of any such device being evacuated, upon an increase in pressure in the exhaust system beyond a predetermined point.

DANIEL MULLAN.
